(57) **CLAIM**

The ornamental design for a right-angle electrical connector, as shown and described.

DESCRIPTION

FIG. 1 is a top, right, front perspective view of a right-angle electrical connector according to our design;

FIG. 2 is a bottom, right, front perspective view thereof;

FIG. 3 is a bottom, right, rear perspective view thereof;

FIG. 4 is a bottom, left, rear perspective view thereof;

FIG. 5 is another top, right, front perspective view thereof;

FIG. 6 is another bottom, left, rear perspective view thereof;

FIG. 7 is a front elevation view thereof;

FIG. 8 is a rear elevation view thereof;

FIG. 9 is a top plan view thereof;

FIG. 10 is a bottom plan view thereof;

FIG. 11 is a left side elevation view thereof; and,

FIG. 12 is a right side elevation view thereof.

In the figure drawings, the short-even broken line is included for the purpose of illustrating environment and forms no part of the claimed design. The dash-dot-dash broken line represents the boundary of the claimed design.

In a preferred embodiment, the nature of this product is an electrical component that can take the form of a right-angle electrical connector, and a right-angle electrical connector housing therefor.

1 Claim, 10 Drawing Sheets
